DESIGN FOR A STATUETTE VASE

Iola G. Marshall, Oakland, Calif.

Application July 9, 1946, Serial No. 131,431

Term of patent 3½ years

(Cl. D29—28)

To all whom it may concern:

Be it known that I, Iola G. Marshall, a citizen of the United States and a resident of Oakland, in the county of Alameda and State of California, have invented a new, original, and ornamental Design for a Statuette Vase, of which the following is a specification, reference being had to the accompanying drawings, forming part thereof, wherein

I claim:

The ornamental design for a statuette vase, substantially as shown.

IOLA G. MARSHALL.
